WALL SHELF

Filed March 30, 1939

WILLIAM F. ORTWIG

INVENTOR.

BY McConkey, Dawson & Booth

ATTORNEY.

UNITED STATES PATENT OFFICE

115,629

DESIGN FOR A WALL SHELF

William F. Ortwig, Benton Harbor, Mich.

Application March 30, 1939, Serial No. 83,917

Term of patent 3½ years

To all whom it may concern:

Be it known that I, William F. Ortwig, a citizen of the United States, residing at Benton Harbor, Michigan, have invented a new, original, and ornamental Design for Wall Shelves, of which the following is a specification, reference being had to the accompanying drawing, forming part thereof.

The figure is a perspective view of a wall shelf, showing my new design.

I claim:

The ornamental design for a wall shelf, as shown.

WILLIAM F. ORTWIG.
